UNITED STATES PATENT OFFICE.

HENRY G. PIFFARD, OF NEW YORK, N. Y.

RECOIL-CUSHION FOR FIRE-ARMS.

SPECIFICATION forming part of Letters Patent No. 281,725, dated July 24, 1883.

Application filed April 23, 1883. (No model.)

To all whom it may concern:

Be it known that I, HENRY G. PIFFARD, a citizen of the United States, and a resident of New York, in the county of New York and State of New York, have invented certain new and useful Recoil-Cushions for Fire-Arms, of which the following is a specification.

The object of my invention is to produce an improved form of cushion possessing greater durability, solidity, and compactness than those now in use, and one that is less liable to sway to one side at the moment of recoil, and that can be produced at such slight cost that it can be brought into common use for military and sporting purposes.

My invention consists of a cushion or pad, of soft rubber or other suitable material or materials, which is applied to the butt of the gun, rifle, or musket, and retained in place by a skeleton butt-plate of any suitable form or material.

In the accompanying drawings, Figure 1 is side view of the butt of a gun, showing my improved recoil-cushion applied thereto. Fig. 2 is an end view of the same. Fig. 3 is a longitudinal section of a portion of the butt on the line *x* *x* of Fig. 2.

A indicates the butt of the gun, and *B* a butt-plate, of iron, brass, horn, hard rubber, or other suitable material. The center of said butt-plate is cut away, as indicated, so as to leave an opening for the face *a* of a cushion or pad, *C*, which is made of soft rubber or other suitable material designed to take up or ease the recoil of the gun when discharged. Said pad or cushion is applied to the butt of

the gun and is retained in place by the skeleton-plate *B*, whose edges grasp the edges of the cushion or pad. The plate *B* is secured to the butt by means of screws, as usual, or in any other suitable manner. The wearing-face *a* of the cushion or pad is flush with the outer surface of the skeleton-plate, or preferably projects slightly beyond such surface, as indicated.

I do not limit myself to the form of the skeleton butt-plate, nor to the shape or number of the openings made thereon. The cushion or pad might be made of other materials or in other ways.

I am aware that rubber cushions or pads intended to diminish the force of the recoil are not new.

What I claim as my invention is—

1. A recoil cushion or pad for fire-arms constructed of soft rubber or other suitable material applied to the butt of the weapon, and projecting through and retained in position by a skeleton butt-plate, of metal, horn, hard rubber, or other suitable material.

2. The combination, with the butt *A*, of the skeleton butt-plate *B*, cut away at its central portion, so as to leave a narrow margin, and a cushion the edges of which are clamped by the butt-plate.

Signed at New York, in the county of New York and State of New York, this 16th day of April, A. D. 1883.

HENRY G. PIFFARD.
